UNITED STATES PATENT OFFICE.

JOSEPH DISTER, OF HAMILTON, OHIO, ASSIGNOR TO AMERICAN CAN COMPANY, OF NEW YORK, N. Y., A CORPORATION OF NEW JERSEY.

TRANSPARENT-SIDED CURVED-WALLED VESSEL.

1,309,615.

Specification of Letters Patent. Patented July 15, 1919.

Application filed December 1, 1913. Serial No. 803,874.

To all whom it may concern:

Be it known that I, JOSEPH DISTER, a citizen of the United States, residing in Hamilton, in the county of Butler and State 5 of Ohio, have invented a new and useful Improvement in Transparent-Sided Curved-Walled Vessels, of which the following is a specification.

This invention relates to an improvement 10 in the art of transparent sided curved walled vessels, and the invention consists in making the walls of the vessel of a sheet metal blank into which is set a flexible transparent window seamed into place while the sheet is in 15 the flat and thereafter curved into form and finished; and in the product or finished article thus made.

In the accompanying drawing which forms a part of this specification, Figure 1 20 is a section of the sheet metal vessel wall shown in the flat and formed with an aperture having shouldered edges ready to receive the flexible transparent sheet; Fig. 2 is a similar section with the flexible transparent sheet added and showing the shouldered edges turned down solidly upon said transparent sheet; Fig. 3 is a similar sectional view of the composite wall showing the same curved into form and its ends 25 united by a side seam; and Fig. 4 is a view of the completed vessel.

Heretofore, the worker in sheet metal, in the manufacture of the large line of articles, like cracker boxes, candy boxes and display boxes in general, that require to have a transparent side through which the contained goods may be seen, has felt obliged to make the vessel containing the transparent window with a flat side and this has generally resulted in such packages or vessels being made of a rectangular form, involving the expense of manufacture incident to such rectangular form and relatively greater than the cost of making the cylindric or curved 40 form of vessel. In the present invention a means is offered whereby such vessels may be made with curved walls following in the

main the usual processes employed in the manufacture of cylindric walled sheet metal ware.

In the said drawing, A is a flexible sheet of tin such as is ordinarily used in the manufacture of tin cans and sheet metal ware. This blank, while in the flat, is perforated with a large window aperture B, the edges 55 of which are folded outwardly to form the double thickness C, and the shoulder flange D. The ends of this blank are formed with the usual hooks E, E, to unite them together. While thus still in the flat a transparent 60 sheet of flexible material F, as for example transparent celluloid cut to the right form and size, is laid into the seat formed by the shoulder flange D, and said shoulder flange is then turned down solidly upon it, after 65 which the sheet is in such condition that it may be and is curved into the form shown at Fig. 3 of the drawing, the ends of the sheet being seamed together to form the body of the vessel which is afterward provided with a bottom G and top of suitable 70 character.

The blank, flat sheet, provided with its flexible transparent portion flatly seamed to it, as above described, is in condition to be 75 and is treated by processes of manufacture the same as though it contained no transparent window, which fact greatly cheapens the cost. And the finished article is cheap, strong, and much less liable to breakage than 80 the ordinary rectangular transparent sided sheet-metal vessel.

It will be noted that owing to the nature of the transparent flexible material, preferably celluloid, and to the method of securing 85 the same in the sheet metal wall,—by pressing the shoulder flange down firmly upon the celluloid held between said flange and a firm seat,—it is possible to make the joint between the sheet metal and the celluloid 90 water-tight and moisture-proof, and such joint is so made in practice.

I claim:

1. A wall for a vessel and comprising a

flat sheet metal bendable member provided with an inset sheet of flexible, transparent material, said wall being adapted to be bent to curved form to form the body wall of a vessel.

2. A can body blank consisting of a bendable sheet of metal and a sheet of flexible transparent material inset therein, the sheet of metal being formed with a three-wall

seam which incloses the edge of said transparent material.

Signed this 25 day of November, 1913, in the presence of two witnesses.

JOSEPH DISTER.
